CORE FORMING MECHANISM

Paul H. Romph, Detroit, Mich., assignor to Packard Motor Car Company, Detroit, Mich., a corporation of Michigan

Application September 10, 1931, Serial No. 562,057

6 Claims. (Cl. 22—10)

This invention relates to the method of and mechanism for forming sand cores.

Core forming machines, in which the sand is blown into the molds by air under pressure, are usually provided with an air chamber and a movable sand transfer member which carries the sand from the supply hopper to position in alignment with, and between, the air chamber and the core box or mold. From the sand transfer member the sand is blown into the core box and packed therein by the air and sand under pressure.

In machines of this character it has been the practice to form the core boxes or molds with an inlet opening and with separate holes or apertures through the walls thereof to permit the escape of air as the sand is deposited in the mold to form the core. Usually these outlet openings are formed in the side walls 20 near the bottom of the core box.

This method of exhausting the air has been found to be quite unsatisfactory due to the fact that when the core is completed and taken from the mold, the sand around each of these holes 25 is found to be loose and not well packed. This undesirable condition is brought about by some of the sand being blown out of the holes with the air during the core filling operation leaving small depressions in the core around each hole. 30 The result is rough, loosely packed and uneven cores.

By the present invention these and other undesirable features in machines of this character are overcome.

The invention contemplates the provision of a core box having a single opening therein and a face plate or cover associated with the opening which is formed with openings or passageways through which the sand and air may be blown into the core box and through which the excess sand and air may be exhausted in substantially the same plane in which they enter. Provision is also made for conducting the sand and air from the core box opening to a position outside the machine. By such construction 45 it is possible to exhaust the entire charge of sand from the transfer member into the mold. The continued pounding of the sand under pressure upon the sand already in the mold 50 results in the sand comprising the core being packed to a greater extent than has heretofore been possible and the excess sand which is not required to form a well packed core will be blown out the top of the core box.

It is an object of the present invention to

provide a core forming machine with improved means for exhausting air and excess sand from the core box.

Another object of this invention is to provide a core forming machine with a core box 60 having a single opening therein to receive sand under air pressure and means adjacent the core box opening and associated therewith through which air and excess sand which may be forced into the core box after the core is completely 65 formed and solidly packed, may be exhausted.

Another object of the invention is to provide the movable sand transfer member of a core blowing machine with improved means for conducting the air and excess sand from the core 70 box.

A further object of the invention is to provide an improved method of forming sand cores whereby the sand and air are blown into the core box and exhausted therefrom in substantially 75 the same plane through a single opening in the core box.

Other objects and advantages of the invention will appear from the following description taken in connection with the accompanying 80 single sheet of drawing which forms a part of this specification, and in which:

Fig. 1 is a side view of the core blowing machine incorporating this invention, shown partly in elevation and partly in section.

Referring to the drawing it will be seen that the machine comprises a base 10 supporting a pair of vertical columns 11, only one of which is shown. Attached to the base and the forward edge of the vertical column is a pneumatic cylinder 12 and operating therein is a piston 13 having a top or table 14 carrying a yoke 15 secured thereto, as by bolts 16. The upper end of the column is inclined forwardly and merges 90 into a hollow blowing head 17 which is positioned 95 directly above the center of the table 14.

A sand hopper 18 is mounted on the supporting column to the rear of the blowing head and has its discharge opening 19 at the same level as the mouth 20 of a sand transfer member 21. 100 The hopper 18 is adapted to contain a suitable core sand, preferably a bond sand, and may be provided with any convenient form of agitator (not shown) to insure the steady flow of sand from the hopper when desired.

The sand conveyer or transfer member 21 is in the form of a hollow elliptical cylinder and is movable from a position beneath the hopper mouth to a position beneath the blowing head. For this purpose the transfer member 21 is sup- 105 110

ported from a frame 22 provided with rollers 23 loosely running in ways 24 in the guides 25 supported between the columns. A pneumatic cylinder 26 supported by a suitable bracket 41 is 5 provided with a piston having a piston rod 27 which is attached to the conveyer. The cylinder is conveniently supplied with compressed air by means of a selective valve at either end thereof, through conduits 28 and 29, to move the conveyer from one position to the other. The back 10 of the frame 22 is extended as at 30 to form a closure slide for the discharge opening 19 of the hopper 18 when the conveyer is moved away.

In its forward position the sand transfer member is directly over the open mouth of a collapsible core box form 31 which is adapted to be received between the arms 32 and 33 of the yoke 15. The core box may be of any desired construction and usually includes a bottom plate 34 15 resting on the bottom of the yoke and suitable end plates and side plates 35 and 36. The interior configuration of the box to form the desired core shape may be effected by properly shaping the inner walls of the bottom, end and 20 side plates. The plates conveniently fit together with the ends between the sides, and are held together by means of dowel pins or are merely provided with engaging tongues and grooves 25 so that they can be quickly assembled and then 30 disassembled as the core is formed so that it can be removed intact. It may be here noted that the only opening provided in the walls of the core box is the large opening in the top thereof through which the sand is received.

35 With the core box parts in position on the yoke and with the piston 13 lowered and the sand transfer member beneath the hopper, sand may be delivered into the transfer member by gravity until it is full. Air is then admitted to 40 the head end of the cylinder 26 and the transfer member is moved to a position between and in alignment with the blower head 17 and the core box, at which time the slide 30 will close the bottom of the hopper. Air is then admitted to 45 the interior of cylinder 12 through a conduit 37 which may be connected to the main air control valve (not shown).

When air under pressure is admitted to the cylinder 12, the piston 13 is moved upwardly 50 carrying the yoke and core box with it. This causes the upper edges of the core box sides and ends to register with a face plate or cover member 38 which is secured to the peripheral flange 39 of the sand transfer member. This plate or 55 cover member 38 forms a closure for both the lower end of the sand transfer member and the opening in the core box. The cover has an opening 40 therein which communicates with the interior of the sand transfer member and 60 through which the sand is blown into the core box. This opening is of such size that the normal consistency of the sand prevents it from falling therethrough by gravity.

As the piston 13 is raised, the core box is carried upwardly to engage a gasket 42 which may 65 be secured to the under side of the face plate 38. The gasket 42 forms an air-tight seal between the core box and the face plate 38 of the sand receptacle when the core box is moved into 70 position to receive sand and air. When the piston and core box are thus raised, the whole sand transfer member is slightly elevated due to the looseness of the rollers 23 on their ways, so that the upper end of the sand transfer member 75 which already registers with the opening in

the blowing head is caused to tightly engage it and form an air-tight joint with the assistance of a gasket 43, if desired. The blowing head may be provided with a suitable perforated baffle plate 44 and an air inlet conduit 45 so that air 80 can be blown at great pressure and properly distributed over the surface of the sand in the sand transfer member to blow it into the core box. Under the high pressure of the air the sand is blown through the opening 40 in the face plate 38 and packed solidly in the mold or core box 31.

Owing to the high pressure of air needed to properly deposit the sand in the core box, it is necessary that means be provided for clamping the sections of the box together. For this purpose one arm 33 of the yoke 15 may be provided with a face which is inclined in the opposite direction from the side of the core box. A wedge 53 is provided having the proper inclination to fit between the inclined surface of the yoke arm 33 and the side of the core box so that when the wedge is tightly pressed in place, the core box is securely clamped between it and the opposite arm of the yoke. The 100 wedge has mounted on it a pair of rods, only one of which 54 is shown, which slide in holes provided in an extended portion 41 of the flange 39 on the bottom of the sand transfer member. The rods are provided on their upper ends with 105 stop nuts 55 to engage with the upper surface of the flange as the yoke is lowered and to assist in withdrawing the wedge. Mounted on the rods between the under surface of the flange portions 41 and the upper face of the wedge 110 are strong coil springs 56 which are instrumental in forcing the wedge into position as the yoke is elevated to bring the upper edges of the core box into engagement with the gasket 42 and the face plate 38 on the sand transfer member. 115

In order that the air may escape from the core box as the sand is deposited therein, and the excess sand which is fed from the sand transfer member after the core box is completely filled and packed may be exhausted, a second 120 passageway 47 is provided in the face plate or cover member 38. The passageway, as shown, is formed in a manner to connect the interior of the core box at the upper end thereof with the atmosphere through the plate 38 when the core 125 box is in operative position. This opening 47 is formed in the cover plate 38 in substantially the same plane as the opening 40 therein so that the air and sand may both enter and be exhausted from the core box without any air 130 passing through the sand forming the body of the core.

Suitably secured as by a nut 48 to the face plate 38 in registry with the exterior port of the passageway or opening 47 is a short length of 135 conduit 50. As shown, this conduit is adapted to telescopically engage another length of conduit 51. The conduit 51 may extend from the machine to any convenient point of deposit. As shown in the drawing, the pipe extends down 140 the side of the support 11, is secured thereto by a bracket 52 and terminates near the floor or other convenient location at which the excess sand is to be deposited. In some instances it may be convenient to extend the conduit 51 to 145 a conveyer which is sometimes employed to supply the hopper 18 with sand.

It will be understood that suitable valves are provided to admit air to the respective ends of the cylinder 26, to the main cylinder 12 and to 150

the blower head 17. The vertical movement of the yoke and core box may be arranged so that the core box is lowered to such a position that it may be conveniently slid onto conveyers and 5 the core and box rolled away for treatment or use.

It will be apparent from the foregoing that simple and efficient means have been provided whereby the sand which is to fill the core box 10 may be packed to a greater extent than has heretofore been possible and whereby a smooth core of uniform contour may be produced. By the present invention it is possible to completely empty the sand transfer member 21 so that the 15 maximum amount of sand is forced into the core box, where in machines previously employed the point at which the core box was completely filled and well packed with sand was more or less a matter of conjecture on the part of the 20 operator. By providing a sand transfer member of a predetermined capacity that is large enough to contain more than enough sand to fill the core box when solidly packed, it is possible to accurately fill and pack the core box 25 uniformly on each operation of the machine. This result is obtained due to the fact that the sand is forced under pressure into the core box until, and even after, the core box is completely filled and packed. Heretofore this has been impossible.

It will also be apparent that the invention, as shown and described, is susceptible of numerous modifications in design without departing from the spirit thereof. For example, the core 30 box itself might be provided with an auxiliary opening adjacent the top thereof similar to that shown in the face plate 38 which could be adapted to exhaust the excess sand and air therethrough. Other changes and modifications will 35 become apparent to those skilled in the art and, therefore, this invention is to be limited only by the scope of the appended claims.

What I claim is:

1. In a core forming machine having a core 40 box with an opening in a wall thereof, a cover member associated with said opening having an inlet opening through which sand and air may be blown into the core box and an outlet opening through which air and excess sand may 45 be exhausted from the core box.

2. In a core forming machine having an air chamber connected to a source of air under pressure, a core box having a single opening at one end thereof, and a hollow sand receptacle 50

55

60

65

70

75

adapted to be interposed between the air chamber and core box; a face plate associated with said sand receptacle adapted to register with the opening in the core box, said face plate having a passageway therein through which sand is blown from the receptacle into the core box and another passageway through which the excess sand and air are exhausted from the core box.

80

3. In a core forming machine having a core box, a blowing head and a sand transfer member movable into and out of alignment with the core box and the blowing head; a face plate associated with said member adapted to contact the core box, said face plate having a passageway therein through which sand may be blown from the transfer member into the core box and another passageway through which excess sand and air may be exhausted from the core box and a conduit connected to said face plate in communication with said exhaust passageway comprising telescoping members adapted to slide one within the other when the transfer member is moved out of alignment with the blower head and the core box.

85

4. In a core forming machine, a core box having a wall formed with a pair of openings therein communicating with the interior of the box and in close proximity to each other, one of said openings forming the sole inlet through which sand may be blown by compressed air and the other of said openings forming the sole outlet through which air and sand may be exhausted from the interior of the core box.

90

5. In a core forming machine, a core box having an open end, a face plate slideable across the open end of said box said face plate having an inlet opening therethrough and an outlet opening communicating with the interior of the box in a relation close to the inlet opening and extending laterally through the side of the face plate, and conduit means connected with the face plate in communication with the outlet opening.

95

6. In a core forming apparatus, the combination of a core box having a top wall with a pair of openings therethrough forming a single inlet and a single outlet for air and sand, means communicating with the inlet opening for blowing sand into the box, and means communicating with the outlet opening for conveying air and excess sand from the box.
